UNITED STATES PATENT OFFICE.

EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

DOBBY HOOK.

Application filed May 22, 1922. Serial No. 562,575.

To all whom it may concern:

Be it known that I, EPPA H. RYON, a citizen of the United States, residing at Waltham, in the county of Middlesex and State 5 of Massachusetts, have invented a new and useful Dobby Hook, of which the following is a specification.

This invention relates to a dobby hook of the general type that is used in large numbers in loom dobbies. These hooks are pivotally connected to the opposite ends of dobby levers and the free ends of the hooks are selectively raised or lowered to form connections for the associated dobby levers with 15 actuating members or knife bars.

My invention relates to improvements in features of construction of such dobby hooks, which will be hereinafter described and more particularly pointed out in the 20 appended claims.

A preferred form of the invention is shown in the drawings in which

Fig. 1 is a side elevation of a pair of hooks and certain associated parts;

25 Fig. 2 is an enlarged side elevation of a dobby lever and hook;

Fig. 3 is a sectional elevation, taken along the line 3—3 in Fig. 1;

30 Fig. 4 is an end elevation, looking in the direction of the arrow 4 in Fig. 2;

Fig. 5 is a sectional plan view, taken along the line 5—5 in Fig. 2;

Fig. 6 is a plan view of two adjacent dobby hooks and levers, and

35 Fig. 7 is a sectional elevation, taken along the line 7—7 in Fig. 6.

Referring to the drawings, I have shown a dobby lever 10 pivoted at 11 on the usual jack 12 and having an upper dobby hook 13 and a lower hook 14 pivotally connected to its opposite ends. The upper hook 13 is positioned by a lifter rod 15 which in turn rests on an indicator lever or finger 16.

The lower hook 14 is directly engaged by 45 another indicating lever or finger 17. The rod 15 is preferably formed of wire of relatively small diameter and the upper end thereof may have a U-shaped return bend, as shown in Fig. 3; thus providing a broad 50 contact surface for the hook 13.

The dobby lever 10 may be of any usual construction and is shown herein as formed of two pieces of sheet metal riveted together at 18 and 19 and having sufficient resiliency 55 so that the ends may be spread apart to admit

the bearing lugs 20 (Fig. 5) of the levers 13 or 14.

The details of this lever need not be further described as they form the subject of a copending application, Serial No. 510, 60 842 filed October 27, 1921, by Elbridge R. Holmes.

The dobby hooks 13 and 14 are reduced in thickness to flat vertical webs at their pivoted ends, as indicated in Fig. 5 and the 65 bearing lugs 20 on each side of the reduced web are preferably formed integral therewith.

The remaining portion of each hook is of the substantially triangular cross section 70 indicated particularly in Figs. 3 and 7. This construction of the hooks possesses numerous important advantages. In the first place, the total weight of the hook is not increased over that of the ordinary hook 75 having a thin flat vertical section. The triangular section, however, without increasing the weight, provides a bearing surface of substantially double the width for the lifter rods 15, as indicated in Fig. 3, or for the 80 fingers 17 which engages directly with the lower hooks.

This triangular section also provides a lower face for the hook which is of substantially the same width as the over-all length 85 of the bearing lugs 20 or the total thickness of the levers 10. The advantages of this feature are indicated in Figs. 6 and 7 which show that the levers 10 are laterally positioned by the edges of these triangular hooks 90 and that the ends of the levers are thus prevented from overlapping and catching on each other in the operation of the dobby.

Furthermore, the strength of the dobby hook for a given weight is materially increased and the form of the hook is particularly well adapted for manufacture by drop 95 forging operations.

Having thus described my invention and the advantages thereof, I do not wish to be 100 limited to the details herein disclosed otherwise than as set forth in the claims, but what I claim is:—

1. A dobby hook having its body portion of substantially triangular cross section 105 with a relatively broad flat lower face.

2. A dobby hook having a hook member at one end and having the other end of reduced thickness with integral bearing lugs projecting from each side thereof, the body portion 110

of said hook being of substantially triangular cross section with a broad flat lower face.

3. A dobby hook having a hook member at one end and having the other end of reduced thickness with bearing lugs projecting from each side thereof, the body portion of said dobby hook being of substantially

triangular cross section and having its lower face of a width as great as the over-all length of said bearing lugs.

In testimony whereof I have hereunto affixed my signature.

EPPA H. RYON.
